FIG. 1 is a perspective view of the luminous welt;
FIG. 2 is a top plan view of the luminous welt shown in FIG. 1;

FIG. 3 is a bottom plan view of the luminous welt shown in FIG. 1;

FIG. 4 is a front elevational view of the luminous welt shown in FIG. 1;

FIG. 5 is a rear elevational view of the luminous welt shown in FIG. 1;

FIG. 6 is a left side elevational view of the luminous welt shown in FIG. 1; and,

FIG. 7 is a right side elevational view of the luminous welt shown in FIG. 1.
